UNITED STATES PATENT OFFICE.

BERNHARD DREYFUS, OF NEW YORK, N. Y.

DESIGN FOR A PENDANT.

SPECIFICATION forming part of Design No. 15,140, dated July 15, 1884.

Application filed May 19, 1884. Term of patent 7 years.

To all whom it may concern:

Be it known that I, BERNHARD DREYFUS, of the city, county, and State of New York, have invented and produced a new and original Design for Pendants, of which the following is a full, clear, and exact description.

The object of my invention is to provide a new and ornamental design for pendants.

Reference is to be had to the accompanying drawing, forming part of this specification, in which a longitudinal or face view of my newly-designed pendant is shown.

The pendant consists of two cone-shaped parts, A and B, each provided at its lower or thicker end with a tuft or ball, C. The upper thinner end of the lower conical part, B, is shown below the tuft or ball C of the upper conical part, A, and on the upper thinner end of the upper conical part, A, is a tuft or ball, D, and a loop, E, is also shown above the upper thinner end of the upper conical part, A. The outer surfaces of the conical parts A and B are comparatively smooth, whereas the surfaces of the tufts or balls C and D are rough and uneven. The lower conical part, B, is slightly longer than the upper conical part, A.

I claim—

1. The herein-described newly-designed pendant, consisting of two conical parts, each having a tuft or ball on its thicker lower end, the thinner end of one conical part being beneath the ball or tuft of the other conical part, substantially as herein shown and described.

2. The herein-described newly-designed pendant, consisting of two conical parts, each having a ball or tuft on its thicker end, one conical part having its upper thinner end below the ball or tuft of the other conical part, and the upper conical part having a tuft or ball on its upper end, substantially as herein shown and described.

3. The herein-described newly-designed pendant, consisting of two conical parts, each having a ball or tuft on its thicker end, one conical part having its upper end below the ball or tuft of the other conical part, and the upper conical part having a ball or tuft and a loop on its upper end, substantially as herein shown and described.

BERNHARD DREYFUS.
